UNITED STATES PATENT OFFICE

BENJAMIN GROSS, OF NEW YORK, N. Y.

DESIGN FOR A FINGER RING OR ARTICLE OF SIMILAR NATURE

Application filed February 10, 1930. Serial No. 34,476. Term of patent 3½ years.

To all whom it may concern:

Be it known that I, BENJAMIN GROSS, a citizen of the United States, residing at New York city, in the county of New York and State of New York, have invented a new, original, and ornamental Design for a Finger Ring or Article of Similar Nature, of which the following is a specification, reference being had to the accompanying drawing, forming a part thereof.

The figure is a perspective view of a finger ring showing my new design. The opposite side of the design is substantially the same as that shown.

I claim:

The ornamental design for a finger ring or article of similar nature, as shown and described.

In testimony whereof I affix my signature.
BENJAMIN GROSS.
